UNITED STATES PATENT OFFICE.

LOUIS MARIE GABRIEL DELAUNAY-BELLEVILLE, OF PARIS, FRANCE, ASSIGNOR TO SOCIÉTÉ ANONYME DES AUTOMOBILES DELAUNAY-BELLEVILLE, OF ST. DENIS, PARIS, FRANCE, A CORPORATION OF FRANCE.

AUTOMATIC CARBURETER FOR EXPLOSIVE-MOTORS.

No. 888,965.

Specification of Letters Patent.

Patented May 26, 1908.

Application filed September 30, 1907. Serial No. 395,205.

To all whom it may concern:

Be it known that I, LOUIS MARIE GABRIEL DELAUNAY-BELLEVILLE, citizen of the French Republic, residing at Paris, department of Seine, in France, have invented certain new and useful Improvements Relating to Automatic Carbureters for Explosion-Motors, of which the following is a specification.

10 This invention has for its object improvements in the carbureters of explosion motors in which two currents are conducted to the motor, one being a combustible current mixed with a certain quantity of air and the 15 other a current of a second or additional quantity of air.

In the novel arrangement, the two currents, one the mixture of primary air and pulverized liquid fuel and the other the supplementary air introduced through the automatic valve, are directed in opposite directions, but instead of penetrating each other mutually, each breaks upon an interposed diaphragm, formed by two conical 25 surfaces arranged base to base, where they spread out and are then projected parallel one with the other in a plane at right angles to the direction of their arrival. In this arrangement, the unvaporized liquid particles 30 mixed with the primary air cannot be projected by their inertia against the upper walls of the apparatus but are so to speak crushed against the guide diaphragm; they are thus more intimately mixed with the air 35 which serves as a vehicle for them, because the mixture with the air, deflected from its original direction, is projected through the orifices of the regulator towards the sockets of the cylinders, at the same time that the 40 supplementary air is projected in the same direction by its encounter with the other face of the guide diaphragm. As shown in the drawing, this diaphragm may be incorporated with the rotary cylinder which regulates the quantities of the gases and is operated by hand by the driver. The seat of the 45 automatic valve for the supplementary air may likewise be incorporated with this rotary part, or on the other hand, as shown in the drawing, it may form part of the fixed 50 socket or casing of the apparatus.

The rotary part and the socket or casing in which it is displaced around their common axis, are provided with ports which are

uncovered and covered to a greater or less extent according to the quantity of gas to be supplied.

The arrangement in question is illustrated in the accompanying drawing, in which:

Figure 1 represents a vertical section on the line $x-x$ of Figs. 2 and 3. Fig. 2 is a vertical section on the line $y-y$ of Figs. 1 and 2. Fig. 3 is a plan view of the valve for the admission of cold air. Fig. 4 is a section on the line $z-z$ of Fig. 2.

65 A is the constant level reservoir.

B is the injector. C the inlet for the primary air. C' the pulverization chamber.

D is the gas mixing diaphragm. This diaphragm is bi-conical or of similar form 70 and is arranged in the axis of a cylinder D' with which it is preferably integral.

E is the box of the diaphragm D. This box is provided with a jacket E' in which the cylinder D' is inclosed in such a manner as to 75 be capable of rotating. This jacket is provided with ports 1—1, arranged opposite ports 2—2 in the cylinder D' which mutually uncover and cover each other more or less on the actuation of an operating part by the 80 driver.

F is the valve for the introduction of cold air, establishing communication between the atmosphere and the box E. This valve is loaded by a spring 3; it opens under the influence of the vacuum.

85 G—G are conduits leading to the cylinders. The right hand conduit and the left hand conduit communicate with each other through the passages 4, 4 formed between 90 the box E and its jacket E'.

g, g, g, g are pipes proceeding from the conduits G, G and terminating at the admission valves of the motor cylinders.

95 The amount of gas admitted to the interior of the cylinder D' is controlled by a rotation of this cylinder, and any suitable means operable from the exterior of the casing may be used for this purpose. In the present instance, the cylinder is provided 100 with a radial finger or pin h which projects through a slot 5 formed in the box E. The latter is provided with a socket H having a tangential passage in which a rod h' reciprocates, this rod being connected to a controlling lever or other suitable device for effecting its reciprocatory movements. The rod h' is provided with a notch or transverse

socket which engages a spherical or rounded head on the outer end of the finger or pin h , sufficient play being provided between the part h and the rod h' as to permit these parts 5 to operate in the respective curved and rectilinear paths.

Having thus described and ascertained the nature of my invention and in what manner the same may be performed, I declare that 10 what I claim is:

1. A carbureter comprising a casing having a tube for the passage of vaporized fuel and primary air, a supplemental air inlet in alinement with said tube, and a conduit 15 extending laterally from said tube, means arranged at the junction of said tube and conduit for deflecting the vaporized fuel and primary air from said tube and the supplemental air from said inlet into said lateral 20 conduit, and a device for controlling in direct proportion the quantities of vaporized fuel and primary air, and the supplemental air admitted to said inlet, into said conduit.

2. A carbureter comprising a casing having a tube for the mixed fuel and primary air, a supplemental air inlet, and a conduit extending laterally from the casing, a ported jacket separating said conduit from the said tube and supplemental air inlet, a valve embodying a cylinder having ports arranged to 30 register with those of the jacket, the cylinder being adjustable to vary the area of said ports, and a deflector arranged within said cylinder for diverting the mixed fuel and primary air and the supplemental air through 35 the ports into said conduit.

3. A carbureter comprising a casing having a box, a tube for conducting mixed fuel and primary air to said box, a valve for admitting a supply of supplemental air to the 40

box in said casing, a ported jacket mounted in said box and alined axially of said tube, a cylinder rotatable within said jacket and having ports arranged to register with those of the latter, a diaphragm mounted within the cylinder and having substantially conical surfaces at its upper and lower sides for diverting the currents of mixed fuel and primary air from said tube and the supplemental air from said valve through the said ports, and a conduit communicating with said ports. 45

4. A carbureter comprising a casing embodying a tube for the mixed fuel and primary air, a valve controlled supplemental air inlet arranged in alinement with the tube, and oppositely extending conduits communicating with the tube and having intercommunicating passages, a ported jacket mounted in the casing for discharging the mixed 50 fuel and primary air and the supplemental air into said conduits, a cylinder rotatable in said jacket and having ports arranged to register therewith for controlling the discharge of fluid into said conduits, a deflector 55 mounted within the cylinder for diverting the currents of mixed fuel and air from said tube and the supplemental air from said inlet into said conduit, and a device operable from the exterior of the casing for adjusting said 60 cylinder. 70

In testimony whereof I have hereunto set my hand in presence of two subscribing witnesses.

LOUIS MARIE GABRIEL
DELAUNAY-BELLEVILLE.
